UNITED STATES PATENT OFFICE.

PAUL RAOULT, OF LIEGE, BELGIUM.

DIGGER FOR BEET AND OTHER ROOTS PLANTED IN LINES.

Application filed December 23, 1925, Serial No. 77,307, and in Germany February 14, 1925.

My invention has for its object to provide a machine of the character in which the penetration of the shares into the ground is automatically effected by the tractive effort of the driving means and the discharging of the extracted roots in regular rows on the ground is effected by means of rotary rollers moving the roots into a screen fitted inside with a worm conveyor or the like.

10 The invention will now be fully described and the features of novelty pointed out in the appended claim.

Reference is to be had to the accompanying drawings in which:

15 Figure 1 is a side elevation of a digger for a double line. Figure 2 is a plan view of the same and Figure 3 a cross-sectional elevation of the share frame shown in Fig. 1.

20 1 designates shares fixed to standards 2 carried by means of a shaft 3 having oppositely pitched screw threads in order to regulate the distance between the two pairs of shares 1. It is sufficient to turn a wrench on the square end of the shaft 3 in order to cause the pairs 25 of shares to approach or separate.

5 indicates parallel arms secured to the shaft 3 and rigidly connected to a sleeve 6 surrounding the axle 7 of the digger.

30 8 indicates arms parallel to the arms 5 and pivoted at their rear end to a shaft 9 connecting the standards 2 of the shares 1, and at their forward end to a shaft 10 journaled in boxes 11 of the frame 12 of the machine.

35 The shares 1 are thus supported by means of a parallelogrammic system oscillating on the axle 7 through the medium of the sleeve 6, which carries a lever 13 connected to a traction ring 18 by means of a chain 14 passing over a roller 15 suspended at small distance from the frame 12 by means of a suspension bow 16, in order to prevent the forward end of the machine from lifting during the digging.

40 Towards its center, the shaft 3 is supported by means of a slotted yoke 18, threaded at its upper end for receiving a screw 19, which oscillates in a sleeve 20 carried by the frame and is actuated by means of a hand-wheel 21. The shaft 9 is also connected by means of a bar 22 to the end of a cranked lever 23 keyed on a shaft 24 journaled in boxes mounted on the frame 12. The lever 23 is locked in position through the medium of a perforated quadrant 25 and a pin.

45 55 These features of construction provide

means whereby the shares 1 are automatically sunk down into the ground, when a tractive effort exerted on the chain 14 causes the upward oscillating of the sleeve 6 and thus the sinking down of the parallelogrammic systems around the axle 7. The lowering of the shares 1 is regulated for the same culture by operating the handwheel 21, but if the shares must be lifted momentarily, by way of example, in order to permit the turning about of the machine, it is sufficient to operate the cranked lever 23, which will cause the lifting of the shares.

50 In order to clean the roots and for throwing them to one side of the machine, in regular rows, I fit loosely to the ends of the axle 7 draft members 26, 26', the rear ends of which are secured to fences 27, 27'. The fence 27 carries a bearing 28 in which is journaled a shaft 29 having fixed thereto a sprocket-wheel 30 forming a tightener for an endless drive-chain 31, receiving motion from a sprocket-wheel 32 mounted on the axle 7, beyond the ground-wheels 33. The drive-chain 31 transmits also rotary motion contrary to 55 the motion of the wheels 33, to a sprocket-wheel 34, the axle of which carries a sprocket-wheel 35 actuating by means of a drive-chain 36 sprocket-wheels 37 mounted respectively on the axles of wooden rollers 38 extending 60 behind the shares 1. The sprocket-wheels 35, 37 with the drive-chain 36 are closed in a casing 39 carried by a plate 40 secured to the fence 27. The axles of the rollers 38 are thus journaled at one end in the casing 39, and at 65 the other end in the casing 41 secured to the fence 27'. On the wooden rollers 38 are fixed laths 42 in order to facilitate the gripping of the extracted roots. The draft members 26, 26' are pivoted to the wheeled axle 7, but are held 70 in substantially fixed relation to the shares 1 by means of bars 43 secured to the fences 27, 27' and hanging on the shaft 9 of the share-standards 2.

75 Behind the rollers 38 is mounted a screen 100 constructed of pipes 44 extending beyond the ends of the rollers 38. The pipes 44 are mounted in a bearer 45 supported by means of a cable or chain 46 connected to a cranked lever 47 held in the adjusted position by the 80 perforated quadrant 25 and secured to a sleeve 48 surrounding the shaft 24. The bearer 45 carries a central shaft 49 of a worm conveyor 50, to which the motion is imparted by means of a sprocket-wheel 51 and a drive- 85 90 95 100 105 110

chain 52 passing over a sprocket-wheel 53 mounted on the wheeled-axle 7. Members 54 connect loosely the said axle 7 with the shaft 49 of the worm conveyer 50,

5 Through the medium of the described mechanism, the beet roots elevated by means of the rollers 38 will tip off round the upper roller and sink on the pipes 44 in order to come in contact with the conveyer 50, which 10 will cause the removing of the earth from the roots and the throwing of the roots in regular rows on the ground. If the roots must be delivered far from the digger, the screen may be made telescopic.

15 Having thus described the invention, what

is claimed and desired to be secured by Letters Patent is:

In a digger, the combination of a digging frame, a wheeled axle supporting the rear end of said frame, share-carrying standards, 20 lower and upper shafts connecting said standards, the ends of the lower shaft being oppositely threaded and fitted in the standards for varying the distance between the latter, a slotted yoke receiving said lower shaft, 25 a screw fitted in said yoke, and means for turning said screw for varying the height of said standards.

In testimony whereof I affix my signature.

PAUL RAOULT.
